UNITED STATES PATENT OFFICE

113,335

DESIGN FOR A COMBINED ILLUMINATED CRUCIFIX AND HOLY WATER FOUNT

Emil Ross, Providence, R. I.

Application December 7, 1938, Serial No. 81,625

Term of patent 7 years

To all whom it may concern:

Be it known that I, Emil Ross, a citizen of the United States, residing at Providence, in the county of Providence and State of Rhode Island, have invented a new, original, and ornamental Design for a Combined Illuminated Crucifix and Holy Water Fount, of which the following is a specification, reference being had to the accompanying drawing, forming part thereof.

The single figure is a front perspective view of a combined illuminated crucifix and holy water fount, showing my new design, the reverse side or back being plain.

I claim:

The ornamental design for a combined illuminated crucifix and holy water fount, as shown and described.

EMIL ROSS.
